SABER SAW UNIT

Donald C. Porter, Covina, Calif.

Application March 3, 1959, Serial No. 54,815

Term of patent 14 years

(Cl. D93—3)

Fig. 1 is a perspective view of a saber saw unit, showing my new design;

Fig. 2 is a side elevation thereof taken from the side opposite to the side shown in Fig. 1; and

Fig. 3 is a rear view thereof.

The essential features of my design reside in the portions shown in full lines.

I claim:

The ornamental design for a saber saw unit, as shown and described.
